UNITED STATES PATENT OFFICE.

DEMPSEY T. BRYAN, OF ROCKYMOUNT, NORTH CAROLINA.

BACK-BAND BUCKLE.

SPECIFICATION forming part of Letters Patent No. 694,727, dated March 4, 1902.

Application filed October 23, 1900. Serial No. 34,053. (No model.)

To all whom it may concern:

Be it known that I, DEMPSEY T. BRYAN, a citizen of the United States, residing at Rocky-mountain, in the county of Edgecombe and State 5 of North Carolina, have invented new and useful Improvements in Back-Band Buckles, of which the following is a specification.

My invention relates to improvements in back-band buckles, all of which will be fully 10 described hereinafter, and particularly referred to in the claims.

The principal object of my invention is to provide a simple and cheap back-band buckle having at the ends of the base-slot laterally-extending essentially U-shaped ears or projections and a clamping member having a slot 15 interlocking with the laterally-projecting U-shaped members, the outer wall of the slot of the clamping member coacting with the inner 20 edges of the walls of the base-slot to lock or clamp the back-band and to allow it to be readily adjusted.

A further object of my present invention pertains to details of construction, which will 25 be particularly pointed out hereinafter.

In the accompanying drawings, Figure 1 is a perspective view of my preferred form of buckle, the back-band omitted. Fig. 2 is a transverse sectional view showing the back-band in position therein. Fig. 3 is a perspective view showing the buckle formed from wire or a strip of metal instead of sheet metal, as illustrated in Figs. 1 and 2.

Referring now to the drawings, A represents a base-plate which, as shown in Figs. 1 and 2, is composed of sheet metal. This base-plate is provided with an elongated back-band-receiving slot *a*, the ends of which are provided with laterally-projecting essentially 35 U-shaped ears or projections *b*. It will be noted that the said laterally-projecting U-shaped ears have the inner ends of their U to communicate with the ends of said slot and to in effect constitute a base-plate with 40 an essentially U-shaped slot, or, in other words, a slot with laterally-extending ends. Projecting from one wall of the base-plate slot is an arm *c*, which has its extremity (when the buckle is completed) bent into the form 45 of a hook-shaped arm *d*.

The clamping member *B* in Figs. 1 and 2 is formed of sheet metal and is provided with

an elongated slot *e*, which is of a length sufficient to embrace the laterally-extending ears *b*, as shown in Fig. 1. Projecting from 55 the outer edge of one wall of said slot *e* is an outwardly-curved arm *f*, which is adapted to rest under the free end of the hook *d*, as illustrated. When the parts are in operative position, the clamping member *B* rests upon 60 the upper face of the base-plate, and the rear web of the clamping member formed by the slot *e* passes through the slot in the base-plate and rests within the laterally-extending U-shaped ears. The back-band passes 65 through the slot in the base-plate and around the rear web of the clamping member and out through said slot in the base-plate. When strain is brought upon the back-band, the curved arm *f* rests under the free end of the 70 hook *d*, and these engaging members serve the double function of locking the two members (the base-plate and the clamping member) together and to hold the trace in position 75 within the hook against accidental removal. In order to place the two said members together after they have been formed either from sheet metal, as shown in Figs. 1 and 2, or of wire or a strip of metal, as shown in Fig. 3, or from other forms of metal or suitable 80 material, the outer web of the clamping member formed by the slot *e* is passed through the base-plate slot (with the clamping member in the position shown in dotted lines, Fig. 1) and the clamping member then turned over to operate 85 position before the hook *d* has been completed. The hook is then completed by turning its extremity down outside of and overlapping the extremity of the arm *f*, which locks the two parts together against removal, 90 as will be readily understood. This construction of a back-band buckle is very simple and cheap to produce and is devoid of any pivotal connections between the parts, while at the same time they are locked in operative position. The ends of the base-plate being bent laterally, as shown, form round corners, which 95 will not injure the animal when the buckle turns to one side, as it sometimes does.

In Fig. 3 I show a buckle constructed in all 100 essential features like that shown in Figs. 1 and 2, only that it is constructed from wire or a strip of metal, which may be square in cross-section, as shown in Fig. 3, or of any

other cross-sectional form. The cross-sectional form of the clamping parts of the buckle may be any desired construction without departing from my invention.

5 Having thus described my invention, what I claim, and desire to secure by Letters Patent, is—

1. A back-band buckle comprising a base-plate having an elongated transverse slot, and 10 essentially **U**-shaped ears connecting the ends of the walls of said slot, said ears extending outward from the base-plate, and a clamping member having a transverse slot of a length and width sufficient to extend from ear to ear, 15 and to receive the inner portions of said **U**-shaped ears, the outer wall of the clamping-member slot located in a line with the slot of the base-plate, substantially as described.

2. A back-band buckle comprising a base-plate having an elongated transverse slot, es- 20 sentially **U**-shaped ears connecting the ends of the walls of said slot, said ears extending outward from the base-plate, said plate having a hook-shaped arm *c*, and a clamping member having a transverse slot of a length 25 and width sufficient to extend from ear to ear and receive the inner portions of said ears, and an arm *f* extending under the hook of the said arm *c*, substantially as described.

In testimony whereof I have hereunto set 30 my hand in the presence of two subscribing witnesses.

DEMPSEY T. BRYAN.
